LUBRICATED JOURNAL BOX

James J. Hennessy, Montclair, N. J.

Application December 14, 1931, Serial No. 580,765
Renewed June 15, 1934

4 Claims. (CL. 308—80)

This invention relates to railway journal lubricators and particularly to means for recovering oil supplied to the journal box hub face and that which escapes beyond the ends of the bearing.

Because of the great weight borne by railway journals, and particularly locomotive driver journals, adequate lubrication of these parts is essential and, particularly where oil is periodically injected from an extraneous source, an excess must be supplied to the parts in order to insure a reasonable margin of safety. Accordingly, with the use of ordinary journal boxes, much oil escapes from the bearings and is wasted.

In an effort to remedy this situation, various pumping devices have been developed for supplying limited quantities of lubricant to each journal, and the boxes have been equipped with various forms of pressure valves and wipers for collecting surplus oil and returning it to the box cellar or reservoir. A lubricating device of the above type is disclosed in my co-pending application, Serial No. 403,027, filed October 28, 1929, which application also illustrates, but does not claim specifically, means for recapturing lubricant which escapes from the bearing on to the box hub face. The present application comprises a continuation of the disclosure, in part, of said co-pending application.

However, the provision of an individual mechanical lubricator for each box considerably increases the cost of the locomotive. A simpler and less expensive lubricating device which also supplies oil in substantially uniform quantities to the box hub face comprises the subject matter of my co-pending application, Serial No. 581,026, filed December 14, 1931. The device therein described is most advantageously used in connection with means for recovering surplus oil which would otherwise be thrown off from the journal and wheel hub by centrifugal force.

The present invention has for its main object the provision of adequate means for preventing loss of lubricant accumulating on the hub face of the journal box.

Another object is to provide means for supplying lubricant directly to the box hub face.

Another object is to provide improved means for recapturing lubricant which escapes longitudinally of the journal beyond the journal box.

These objects and others are attained by the structure illustrated in the accompanying drawing, in which—

55 Figure 1 is a side view of a locomotive driving

box and journal, portions being sectioned for clearer illustration.

Figure 2 is an outside view of the hub face of the box.

Figure 3 is a view corresponding with Figure 5 but showing a modification.

Figure 4 is a view of the hub face of the modified form.

Figure 5 is a vertical transverse section through another form of driving box and wheel hub.

The invention is illustrated as applied to a locomotive driving box 1 (Figures 1 and 2) supported on journal 2 through the usual bearing brass 3. Spacer 4 at the bottom of the box 15 mounts a sub-cellar 5 upon coiled springs 6. Oil distributing packing, shown as comprising a series of felt strips 7, is in turn carried by the sub-cellar and maintained snugly in engagement with the journal by springs 8.

Oil is supplied to the journal through a passage 9 in the top of the driving box and continuing through the bearing brass 9, which passage communicates with a longitudinal slot 10 and angularly disposed slots 11 in the under surface 25 of the brass. This box is particularly adapted for use with an oil distributing system, such, for example, as is disclosed in my co-pending application, Serial No. 581,026 mentioned above. However, each box may be equipped with an individual pump or supply reservoir, if desired.

Excess lubricant escaping to the hub face of the box and wheel hub serves to lubricate these parts. A portion of the escaping oil will be transferred to the wheel hub and centrifugally thrown off by a deflector ring 11 secured to the hub 12 and inclined outwardly from the center thereof at an angle of approximately forty five degrees. The box hub face 13 is provided with a circular groove 14 and a strip 15 secured thereto and extending outwardly a sufficient distance to slightly overlap deflector ring 11 when the wheel hub and box are at their points of greatest separation.

The collector ring is disposed in such a manner as to direct the deflected lubricant downwardly around the same and into an upwardly inclined portion at the bottom. Strip 15 is interrupted at the bottom and the lower portion 50 of the ring is formed by an arcuately depressed portion 16 of the spacer 4 which extends outwardly beyond the box hub face. A hole 17 in portion 16 permits the collected oil to drain into an inclined trough 18 beneath the spacer, from 55

whence the oil may be recovered through a draw-off pipe 19.

Oil escaping inwardly along the journal is recovered by means of a series of wiper plates 30 secured to a pair of wire rings 31 within a cup-shaped cover 45 forming a restricted enclosure surrounding the journal. Regular spacing of the wipers is maintained by a wire 32 wound spirally around wires 31. Lubricant collected by 10 the wipers drips into the cover 45 or directly onto the floor of the box and passes into trough 18 through an opening 33. Wings 34 and splash plates 35 on the sub-cellar 5 and inside of the box, respectively, also assist in preventing loss 15 of lubricant.

In Figure 3 and 4, the box and cellar dimensions prevent the use of a full circle collector ring. Strip 20 secured in circular groove 21 in the box face ends at points A on each side, and 20 angle plates 22, secured to the ends of strip 20 within groove 21, halt the flow of oil downwardly in the groove and divert the same through a hole 23 in the box face and into short pipes 24 which lead into cellar 25.

Sub-cellar 26 is supported above the cellar 25 floor on coiled springs and is located below the normal level of oil in cellar 25 so that oil distributing packing (not shown) supported on plate 27 will be partially immersed therein and 30 lubricant carried thereby upwardly to the journal by capillary attraction.

Oil squeezed outwardly beyond the end of brass 36 serves to lubricate the box hub face, and shallow grooves 37 in the box face assist the 35 flow of excess lubricant outwardly to the collector groove 21. The circulation of oil thereby effected substantially decreases the frequency with which the oil supply in the box must be renewed.

The form of box and cellar shown in Figures 40 3 and 4 is also adapted for the application of an individual pumping device and reservoir similar to that disclosed in my co-pending application, Serial No. 403,027, mentioned above in which 45 case oil circulation would be maintained within each box. This last-mentioned application also shows but does not specifically claim co-operating collecting and deflecting rings for recapturing excess oil.

In Figure 5 is shown means for applying lubricant directly to the hub face of the journal box. The top of the box is provided with a downwardly inclined passage 38 opening into the hub 50 face 39 above bearing 40. Oil passage 38 is arranged for connection with a conduit 41 leading from an outside source of lubricant (not shown) and suitable means may be utilized for returning recaptured oil from draw-off pipe 44 to the supply tank. The deflector and collector 55 rings 42 and 43 respectively, and other oil recapturing elements are the same as corresponding elements in Figures 1 and 2.

The principles of the present invention are not limited in application to locomotive driving boxes but may be advantageously applied to other railway journal boxes. Moreover, the means shown for supplying oil to the journal 5 itself are not essential, nor is the type of journal box illustrated. The embodiments shown may be modified in these and other respects as to details without departing from the spirit of the invention and exclusive use of all such variations as come within the scope of the appended 10 claims is contemplated.

What is claimed is:

1. In combination, a railway vehicle wheel and a journal box therefor, said wheel and box 15 having opposing faces, means for supplying lubricant to said faces, and means for preventing loss of said lubricant comprising a ring-like deflecting element on said wheel face, a cooperating ring-like collecting element on said box 20 face, grooves in said box face leading outwardly to said collecting element for assisting the flow of oil thereto, and an oil recovery passage leading from said box face adjacent the lower part of said collector element. 25

2. In combination, a railway vehicle wheel having a journal, and a journal box therefor, said wheel and box having opposing faces, a spacer in the lower part of said box, means for supplying oil to said faces, and means for preventing loss of said oil comprising a deflector ring on said wheel face and surrounding said journal, a cooperating ring-like collector element on said box, said spacer having an arcuate depression forming the lower portion of said 30 collector element, and an oil recovery passage 35 leading from said depressed portion of said spacer.

3. In combination, a vehicle wheel having a hub face and a journal, a journal box therefor 40 with a face abutting said hub face, a spacer connecting the sides of said box beneath said journal, means for supplying lubricant to at least one of said faces, and means for preventing loss 45 of said lubricant including a collector ring extending around the outer edge of said box face, part of said ring being on said spacer.

4. In combination, a locomotive driver with a center hub structure arranged for mounting an axle and a driving pin, a driving box, said hub structure and box having abutting radial faces, the hub face extending radially beyond the box space, means for supplying lubricant to 50 said faces and means for preventing loss of said lubricant comprising a deflecting element projecting at an angle from said hub face and a circular groove-like depression in said box face and receiving said deflecting element, and a recovery passage leading from said depression. 55
